PLASTERER'S DARBY

Edward A. Whalen, Chicago, Ill., assignor to Wha-Lite Products, Chicago, Ill., a copartnership composed of Edward A. Whalen and Sidney F. Lundberg

Filed Oct. 14, 1960, Ser. No. 62,494

Term of patent 14 years

(Cl. D51—1)

Fig. 1.

Fig. 2.

I claim:

The ornamental design for a plasterer's darby, substantially as shown and described.
